DESIGN FOR A COMPARTMENTED JAR OR THE LIKE

Charles W. Lauby, Vincennes, Ind.

Application February 2, 1948, Serial No. 144,224

Term of patent 14 years

(Cl. D58—25)

To all whom it may concern:

Be it known that I, Charles W. Lauby, a citizen of the United States, residing at Vincennes, in the county of Knox, State of Indiana, have invented a new, original, and ornamental Design for a Compartmented Jar or the like, of which the following is a specification, reference being had to the accompanying drawings, forming part thereof.

Fig. 1 is a top plan view of a compartmented jar or the like, showing my new design.

Fig. 2 is a side elevational view of a compartmented jar or the like, and,

Fig. 3 is an end elevational view thereof.

I claim:

The ornamental design for a compartmented jar or the like, as shown.

CHARLES W. LAUBY.
